INVENTOR

UNITED STATES PATENT OFFICE.

RAYMOND H. AVERNS, OF COVENTRY, ENGLAND, ASSIGNOR TO J. & J. CASH, LIMITED,
OF COVENTRY, ENGLAND, A CORPORATION OF GREAT BRITAIN AND IRELAND.

DESIGN FOR BRAID OR TRIMMING.

43,978.

Specification for Design.

Patented May 13, 1913.

Application filed February 15, 1913. Serial No. 748,727. Term of patent 3½ years.

To all whom it may concern:

Be it known that I, RAYMOND H. AVERNS, a subject of the King of Great Britain, residing at Coventry, county of Warwickshire, England, have invented a new, original, and ornamental Design for a Braid or Trimming, of which the following is a specification, reference being had to the accompanying drawing, forming a part thereof.

The figure is a face view of a piece of braid or trimming showing the design.

I claim—

The ornamental design for a braid or trimming as shown.

RAYMOND H. AVERNS.

Witnesses:

J. C. GEO. GILES,
ARTHUR J. WOOD.
